Filed Oct. 15, 1971, Ser. No. 189,557

Term of patent 14 years

Int. Cl. D9—03

U.S. Cl. D9—219

FIG. 1

FIG. 2

FIG. 3

FIG. 4

FIG. 1 is a perspective view of a food container or similar article embodying my new design;

FIG. 2 is an end view;

FIG. 3 is a side view; and

FIG. 4 is a bottom view

The characteristic feature of my design for a food container or similar article resides in a divider therefor which has opposed vertical surfaces and an outwardly convex channel which extends in both side walls and across the bottom of the container.

I claim:

The ornamental design for a food container or similar article, as shown.
